Primary Examiner — Wendy L Arminio*Assistant Examiner* — Maheen Khurshid(74) *Attorney, Agent, or Firm* — Wolf, Greenfield & Sacks, P.C.(57) **CLAIM**

The ornamental design for an inhaler cup, as shown and described.

DESCRIPTION

FIG. 1 is a top, front, perspective view of an inhaler cup; FIG. 2 is a top, rear, perspective thereof;

FIG. 3 is a bottom, rear perspective view thereof;

FIG. 4 is a front view thereof;

FIG. 5 is a rear view thereof;

FIG. 6 is a left side view thereof;

FIG. 7 right side view thereof;

FIG. 8 top view thereof; and,

FIG. 9 bottom view thereof.

The dash-dash broken lines show portions of the inhaler cup that form no part of the claimed design. The long-dash-

(Continued)

short-dash broken lines represent boundaries of the claimed design and form no part of the claimed design.
